UNITED STATES PATENT OFFICE.

GEORGE RUMSEY, OF GRAND RAPIDS, MICHIGAN.

MACHINE FOR MAKING BARBED STAPLES.

SPECIFICATION forming part of Letters Patent No. 296,628, dated April 8, 1884.

Application filed September 5, 1883. (No model.)

To all whom it may concern:

Be it known that I, GEORGE RUMSEY, of Grand Rapids, in the county of Kent and State of Michigan, have invented new and useful 5 Improvements in Machines for Making Barbed Staples; and I do hereby declare that the following is a full and complete description thereof.

The object of the aforesaid improvement in 10 making staples is to cut from a reel of wire a certain length or blank, and bend the same into a staple, and at the same time serrate or barb the prongs thereof that they may hold firmly in the material into which they may be driven.

15 The construction of the mechanism and the arrangement and operation of the same for the above-specified purposes are as follows, whereof the annexed drawings are an illustration, in which—

20 Figure 1 shows a front elevation of the machine. Fig. 2 is a plan view. Fig. 3 is an end elevation. Figs. 4, 5, 6, 7, 8, and 9 are detached sections, to which reference will be made.

25 Like letters of reference refer to like parts in the several views.

On a suitable frame are the standards A, B, and C, in which is journaled a main driving-shaft, D. Above said shaft, and parallel therewith, is a shaft, E, journaled in the standards 30 B and F, Fig. 1. On the end of the shaft E is a wheel or disk, G, an enlarged detached view of which is shown in Fig. 4. In the side of the disk G is a recess, in which is fitted closely 35 but detachable a pair of barbing plates or dies H I. Interposed between said dies is a bending slide, J, closely fitting but free to move radially between them. The barbing-dies are secured in the recess by the clamps K and K',

40 Figs. 4 and 5. A detached view of one of the clamps is shown in Fig. 8, in which it will be seen that the clamp consists of a rib, L, provided with a narrow plate forming a back to the rib. The width of said back is equal to 45 the thickness of the two barbing-dies and rib, as shown in Fig. 5, in which it will be observed that the barbing-dies and bending-slide do not fill the depth of the recess by so much as the thickness of the binding-plate M, placed on 50 over the recess in a rabbet, that the plate may be flush with the side of the disk, and at the same time bind the clamps and dies firmly in

the recess by means of screw-bolts inserted therein, as seen in the drawings. While the binding-plate M secures the clamps and the 55 barbing-dies transversely in the recess, the said dies are bound edgewise therein by the set-screw N, inserted through the edge of the disk, to the clamp K', Fig. 4. It will be obvious that on turning the set-screw in the proper direction it will force the clamp K' and the barbing-dies hard against the farther side of the recess, and hold them securely and firmly therein without obstructing a free radial movement of the bending-slide J, interposed between the barbing-dies and clamps. 60

The bending-slide is retained between the barbing-dies and clamps by means of a stud, a, Fig. 4, projecting from the rib of the clamp K into a notch cut in the edge of the bending-slide, as shown in said Fig. 4. A portion of the barbing-die H is represented as broken away, that the notch and pin may be seen. The binding-plate in said Fig. 4 is shown as removed, but in place in Fig. 5. It will be 75 noticed in said Fig. 4 that the barbing-dies project beyond the periphery of the disk. In this position they are maintained by the set-screw O, projected through the disk to a bar, P, on which the barbing-dies stand, and thereby prevented from being forced radially inward, but which may be forced outward by the adjusting-screw O acting on the said bar. It will also be noticed that the bending-slide projects beyond the barbing-dies; in this relation 80 to the said dies it is maintained by a spring, Q, passing upward through the bar P to the end of the bending-slide, and upon said spring the slide rests, and is thereby forced radially outward, for a purpose presently shown. 85

R is a disk corresponding to the disk G, and arranged in relation therewith, as shown in Figs. 1 and 3. Said disk R is secured to the main shaft D, and is provided with barbing-dies corresponding to the barbing-dies of the 90 disk G, and co-operate therewith for barbing a staple, as hereinafter described. The barbing-dies in said disk R may be secured therein, substantially in the same way as are the barbing-dies in the disk G, or they may be secured therein by any other suitable device and made adjustable by a set-screw and bar. In the disk R there is no bending-slide, but a 95 firm base between the barbing-dies, so that 100

when the two disks revolve one upon the other the projecting end of the bending-slide of the disk G will pass between the barbing-dies of the disk R and impinge upon the base between them, which will force the bending-slide back into the disk that it may not project beyond the barbing-dies while barbing a staple. Further attention will be called to this part of the operation of the disks.

- 10 On the extreme end of the shaft D is an eccentric, U, Fig. 3, provided with an arm, V. To the end of the arm is connected one end of a link, W, whereas the opposite end is pivoted to a block, A', and the middle thereof is 15 pivoted to a cutter-bar, B', for operating the cutter C'. The cutter-bar is arranged to move in the guide or ways D'. An enlarged detached view of the cutter is shown in Fig. 9. The wire-cutting device is adapted to cut 20 the wire diagonally across, to obtain a pointed end to the prongs of the staple. For that purpose the wire is run through a tube, E', Fig. 2. An enlarged detached view of the same is shown in Fig. 9, in which it will be observed 25 that the end of the tube is cut diagonally across, forming an inclined plane, to which the cutter is adjusted. It will be obvious that as the wire moves through the tube it will be cut off by the cutter as the cutter moves over the end 30 of the tube at an angle corresponding to that of the end of the tube or the inclined plane, which will give pointed ends to the prongs of the staple made therefrom.

The wire is fed to the machine by the lever 35 F', pivoted in the standard G' by a link, I'. The lever F' is connected to a lever, H', pivoted in a standard, J'. The inner end of the lever H' extends to and terminates between the cheeks of the cam K'', as shown in Fig. 2. 40 Said cam is secured to the shaft D, and vibrates the lever H'; also the feed-lever F', connected thereto by the link I'. On the end of the feed-lever is a block, L', having a hole therein large enough to admit the wire d to pass freely 45 through. In said hole may be serrations or teeth pointing toward the cutter, so that as the lever vibrates horizontally the wire is crimped in the block, and by means of the inclined teeth, the said wire is carried along in the direction 50 of the arrow, but will slide over the wire when the lever moves in the opposite direction, as the hole in the block will then cease to cramp the wire. The stroke of the lever is of sufficient length to carry the wire far enough along 55 for a staple-blank. That the wire may not move too easily, also to steady and give tension to the same, that it may be fed to the machine without bending or kinking, it is passed under the arm M', to which is hung a weight, 60 N', that the wire may draw with more or less resistance and consequent tension.

The two disks G and R are operated by the cog-wheels O' and P' on the shafts D and E, power being applied to the shaft D. On said 65 shafts D and E are respectively the fly or balance wheels Q' and R'.

Having described the several parts of the

machine and the arrangement of the same, the practical operation thereof is as follows:

The wire of which the staples are to be 70 made is taken from a reel and passed under the lever M', thence through the block L' of the feed-lever, the vibration of which carries the wire forward through the tube E', thence in front of the bending-block n, across the 75 notch m therein, as shown at a' in Fig. 1. At this instant the wire is cut off by the timely movement of the cutter during the general movement of the machine. The wire or staple-blank thus cut off is caught by the end of 80 the bending-slide, which at this moment is about to enter the notch m of the bending-block. As the end of the slide passes through the notch n, the piece of wire or blank is bent thereby against the sides of the notch, forming 85 a staple around the end of the slide, and at the same time carrying the staple along, bringing the prongs thereof between the barbing-dies of the upper and lower disks, thereby 90 barbing both sides of the prongs of the staple. 95 While the barbing is being done the bending-slide is pushed inward by its contact with the bottom between the barbing-dies of the lower disk, which releases the staple from the end of the slide, allowing it to drop into a receptacle under the machine. The resiliency of the spring q forces the slide again outward 100 the instant the barbing is done and the barbing-dies have passed from each other. During the operation of bending and barbing the staple, the wire is again fed forward and a piece 105 or blank cut off, which is immediately caught by the now projecting end of the bending-slide, and, as before, carried through the notch m, and bent and barbed, as in the former instance, and so on continuously, as the wire is fed to the machine. A blank is cut off, bent, and barbed during the revolving movement of the disks and the general operative action of the machine.

The opportune action of the cutter is effected by the eccentric U and arm V, above described. The throw of the eccentric may be so adjusted as to operate the cutter-bar and cutter to cut different lengths of blanks as 115 the size of the staples to be made may require, and which, as aforesaid, are cut diagonally across, making a point to the ends or prongs of the staple.

The further purpose above alluded to of 120 the binder or lever M' is to confine the wire, so that it may not push back nor kink when the feed-block of the lever F' moves back to take another grip on the wire to draw it forward to be operated on, as above set forth.

It may be proper to remark here that the blank for a staple when cut off is retained 125 momentarily in position against the binding-block n until the bending-slide strikes it by a pressure-foot, (not shown in the drawings, as it forms no part of this invention,) and is similar to those used in all machines of this class, differing from such only in being adapted to its place, and is operated by suitable mechan-

ism conjointly with the general movement of the machine, as herein described.

What I claim as my invention, and desire to secure by Letters Patent, is—

- 5 In a machine for making staples, the wheel or disk G, having in the side thereof a recess, in which are fitted barbing plates or dies secured therein by clamps and set-screws N O, plate P, and binding-plate M, and interposed
10 between the said barbing-dies, a bending-slide having a reciprocal radial movement

between said plates or dies, and retained therein by a notch and pin and in a projected position for bending a staple-blank by a spring, Q, substantially in the manner as described, 15 and for the purpose specified.

In testimony whereof I affix my signature in presence of two witnesses.

GEORGE RUMSEY.
